(57) **CLAIM**

The ornamental design for a wearable stuffed animal tail with belt clip, as shown and described.

DESCRIPTION

FIG. 1 is a perspective view of a wearable stuffed animal tail with a belt clip, showing my new design;

FIG. 2 is a front elevational view of the invention;

FIG. 3 is a rear elevational view of the invention;

FIG. 4 is a left-side elevational view of the invention;

FIG. 5 is a right-side elevational view of the invention;

FIG. 6 is a top plan view of the invention; and,

FIG. 7 is a bottom plan view of the invention.

The broken lines showing a person in FIG. 1 are included for the purpose of illustrating the invention in use, and form no part of the claimed design.

The broken lines on the surface of the claimed design in FIGS. 2 and 3 represent stitching.
